ABSTRACT

A reduction gearing relating an electric motor for driving a feed wheel and a driving shaft carrying the feed wheel includes helical gears at least one of which is adapted to be displaced axially by the thrusting force resulting from the reaction force of the can opening operation. This thrusting helical gear is either mounted tightly on a thrusting shaft for movement of the gear with the shaft or alternatively, the helical gear may be mounted loosely for thrusting movement on a shaft adapted not to thrust. A resilient interconnecting member is actuated by the thrusting movement of the helical gear and makes a latching piece engage a pivoted hand lever carrying a rotary cutter, thereby maintaining the hand lever in the lowered or can severing position. The disappearance of the reaction force results in the disengagement between the hand lever and the latching piece and the displaced helical gear is returned by the restoring force of the resilient interconnecting member.

MOTOR OPERATED CAN OPENER

BACKGROUND OF THE INVENTION

In a conventional motor operated can opener, a can is opened in such a manner that a rotary cutter penetrates the outer edge of a can lid with the end seam of the can disposed on a feed wheel and the can is rotated by the feed wheel. For the purpose of maintaining the rotary cutter in its can severing position during a can opening process, either the rotary cutter or the feed wheel is adapted to be movable against a housing and is displaced in accordance with the variation of the reaction force exerting on the feed wheel during can opening process, thereby making a complicated and delicate holding mechanism for a rotary cutter carrying hand lever or handle to work. Because either the rotary cutter or the feed wheel is displaced just when the rotary cutter is penetrating the can lid, utilization of such a complicated holding mechanism requires skillful operations of the handle to make the rotary cutter penetrate the can. Further, such a conventional can opener is expensive in its manufacturing cost because of the complicated structure for making movable either the rotary cutter or the feed wheel and has the disadvantage of possible troubles.

SUMMARY OF THE INVENTION

The present invention improves the motor operated can opener in construction and operation in order to eliminate the disadvantages mentioned above and its object is to provide a motor operated can opener simple in construction with which any one without mechanical skill can open cans easily. The feature of the present invention lies in the introduction of helical gears in the gearing for transmitting torque from the electric motor to the feed wheel. At least one of the helical gears is mounted for thrusting motion. The hand lever carrying the rotary cutter is pivoted adjacent the outer end of the front vertical wall of a housing for vertical swinging motion and is adapted to be latched in its can severing position by the cooperation of a latching piece and a resilient interconnecting member actuated by the helical gear for thrusting. When the reaction force appears and the electric motor is loaded as the result of the can opening operation, the helical gear is not only rotated by the increased driving force but also is pushed forwardly, thereby actuating the resilient interconnecting member to make the latching piece maintaining the hand lever in the can severing position. When the electric motor is unloaded, the thrusting helical gear is returned by the resilient interconnecting member and the hand lever becomes free.

It will be understood from the salient relationships just described and following descriptions that the present can opener is simplified in structure and operation by the elimination of the conventional complicated mechanism prepared specially for latching the hand lever. Thus, the can opener is inexpensive and can be operated satisfactorily by users mechanically unskilled.

In the drawings

FIG. 1 is a front elevational view of a motor operated can opener;

FIG. 2 is a rear elevational view of the can opener with a rear cover being taken away;

FIG. 3 is a fragmentary view partly in vertical section of the can opener showing the unloaded situation;

FIG. 4 is a view similar to that of FIG. 3 but showing the can severing situation.

Referring to the figures, a motor operated can opener according to the present invention comprises a housing A, can feeding mechanism B, a lever latching means C, a cutter assembly D and a switching structure E. The housing A comprises a base plate 10, side walls 11, a front wall 12, a top plate 13, and a rear cover (not shown). On the inner surface of the front wall 12, a frame 14 is secured on which the can feeding mechanism B and the latching means C are mounted. A can supporting lug 15 to hold a can on its side wall is attached by means of screws adjacent the center of the outer surface of the front wall 12. In the can feeding mechanism B, a peripherally toothed feed wheel 16 is mounted on the outer extreme of a driving shaft 17 which projects through the front wall 12 and the frame 14 and is journaled rotatably in a bearing boss 18 extending inwardly from the frame 14. In order to drivingly relate an electric motor 19 mounted in the housing A and the driving shaft 17, there is provided a reduction gearing 20. The reduction gearing includes a large helical gear 21 mounted on the inner extreme of the driving shaft 17. A helical gear 22 of small diameter being in mesh with the large helical gear 21 and a thrusting large helical gear 23 are mounted tightly on a thrusting shaft 24 one end of which is received rotatably and reciprocatingly in a bearing support 25 formed on the frame 14. The thrusting helical gear 26 formed on the shaft of the electric motor 19. Instead of using the thrusting shaft 24, the thrusting helical gear 23 may be mounted loosely for thrusting movement on a shaft adapted not to thrust. The helical threads of the gearing 20 are so oriented that the axial component resulting from the reaction force of the can opening operation can displace the thrusting gear 23 from the position shown in FIG. 3 to that shown in FIG. 4. Now in the latching means C, an inverted Y-shaped resilient interconnecting member 27 is secured on the frame 14 at its both extreme ends of the limbs 27' by means of screws 28. The forked portion of the resilient interconnecting member 27 is intersected by the thrusting shaft 24 to be bent by the thrusting helical gear 23 and the upper end of the resilient interconnecting member 27 is secured on the inner end of a latching piece 29 which is contained reciprocatingly in a cylindrical holder 30 formed integrally with the upper end of the frame 14. The resilient interconnecting member 27 not only relates the thrusting helical gear 23 and the latching piece 29 but also serves as a means for biasing the gear 23 to return it to the position of FIG. 3. The elastic biasing force exerted by the resilient member 27 is adjusted to be weaker than the axial thrusting force resulting from the reaction force of the can opening operation thereby allowing the thrusting shaft 24 to displace in the direction indicated by an arrow 31 but to be enough to return the thrusting helical gear 23 when the feed wheel 16 is unloaded or undriven. Next in the cutter assembly D, a hand lever 32 is positioned against the front wall 12 and is pivoted by means of a pivot 33 and a nut 34 for vertical swinging movement. The hand lever 32 has an upper face 35 and a vertical front face 36 on the lower edge of which a hook 37 is provided as a member to engage the latching piece 29 when the hand lever 32 is lowered to move the switching structure E to its circuit closing position. The hand lever 32 carries a planar spring 38 which is disposed on the upper edge of the

can to be opened in order to prevent vibrations involved in the can severing operation and to raise the hand lever 32 after the completion of the can opening operation. A circular rotary cutter 39 is mounted rotatably on a stud 40 extending from the hand lever 32 in a inclined downward direction. Adjacent and over the mount of the rotary cutter 39 is projecting an arm 41 from the hand lever 32. A headed hanger 42 is provided in an aperture of the arm 41 and a permanent magnet 43 is secured on the lower end of the hanger 42. The switching structure E is contained within a switch box 44 and includes a push button 45 projecting through the top plate 13. The push button 45 engages a resilient movable contact 46 at its lower end and the movable contact 46 cooperates a fixed contact 47. The contacts 46 and 47 are adapted to contact each other by the downward movement of the push button 45 depressed by the hand lever 32 and to close the motor energizing circuit.

In the operation of the device, the hand lever 32 is raised from the position of FIG. 1 and then the end seam 48 of a can is placed on the feed wheel 16. Then, lowering the hand lever 32 makes the rotary cutter 39 penetrate into a can lid 49 near its outer edge and moves the switching structure E into its circuit closing position. The electric motor 19 thus energized rotates the feed wheel 16 through the gearing 20, thus feeding the can and the rotary cutter 39 severs the can lid 49. At the same time, the helical gear 22 and the helical gear 23 are displaced forwardly of the housing A from the position of FIG. 3 to that of FIG. 4 keeping meshing engagement with gears 26 and 21 on account of the axial force resulting from the reaction force of the can opening operation and exerting on the thrusting shaft 24. The resilient interconnecting member 27 is bent to establish the engagement between the latching piece 29 and the hook 37, thereby latching the hand lever 32 in its can severing position. When the reaction force disappears as the completion of the can opening operation, the gears 22 and 23 are returned from the position of FIG. 4 to that of FIG. 3 by the biasing force of the resilient member 27 which also makes the latching piece 29 disengage the hook 37. The hand lever 32 which has been made free, is raised slightly by the restoring force of the planar spring 38 or the movable contact 46 to open the motor energizing circuit. After raising the hand lever further, the can be removed from the can opener. The can lid 49 cut off is attracted and held by the magnet 43, being prevented from dropping in the can.

What we claim is:

1. A motor operated can opener comprising a housing, an electric motor mounted in said housing, a driving shaft extending rotatably through the front wall of said housing, a peripherally toothed feed wheel mounted on the extending end of said driving shaft, and being adapted to engage the lower end of the end seam of a can, a reduction gearing for relating said feed

- wheel and said electric motor, said gearing comprising a train of helical gears and one of said helical gears being adapted to be displaced axially under the thrust resulting from the working gearing, a hand lever positioned against and pivoted to said front wall for vertical swinging motion between positions adjacent and away from the feed wheel, a rotary cutter for cutting the lid of the can and carried by said hand lever, a switching structure contained in said housing, said switching structure including a push button projecting through the top plate of said housing and adapted to be depressed to move said switching structure into the motor energizing position, a latching piece extending reciprocatingly through said front wall, said latching member being adapted to engage the hand lever thereby latch said hand lever in its lowered or can severing position and a resilient interconnecting member relating said thrusting helical gear of the reduction gearing and said latching piece, the elastic force of said resilient interconnecting member being weaker than the axial thrusting force resulting from the reaction force of can opening operation and exerting on the thrusting helical gear to establish the engagement between said latching piece and said hand lever on disappearance of said reaction force.
2. A motor operated can opener described in claim 1 in which said thrusting helical gear is mounted tightly on a thrusting shaft supported reciprocatingly against said housing.
3. A motor operated can opener described in claim 1 in which said thrusting helical gear is mounted loosely on a shaft for reciprocating movement.
4. A motor operated can opener described in claim 1 in which said resilient interconnecting member is an inverted Y-shaped member secured against said housing at two limb portions, engaging the latching piece at the other end and being actuated by the thrusting helical gear at its intermediate forked portion.
5. A motor operated can opener described in claim 1 in which said resilient interconnecting member is an inverted Y-shaped member secured against said housing at two limb portions, engaging the latching piece at the other end and having its forked intermediate portion engaged by said thrusting helical gear and is adapted to bend resiliently when actuated by the thrusting helical gear and to function to return said thrusting helical gear on the disappearance of the can opening reaction force exerting on said feed wheel.
6. A motor operated can opener described in claim 1 in which said hand lever carrying said rotary cutter comprises a top face and a vertical face with its lower portion bent towards said front wall of the housing to form a latched member and this latched member is engaged by said latching piece extending through said front wall thereby maintaining said hand lever in the can opening position during the can opening operation.
